UNITED STATES PATENT OFFICE.

JAMES MACKAYE, OF CAMBRIDGE, MASSACHUSETTS, ASSIGNOR TO STONE & WEBSTER, OF BOSTON, MASSACHUSETTS.

PROCESS FOR PRODUCING CHLORIDS OF CARBON.

No. 880,900.

Specification of Letters Patent. Patented March 3, 1908.

Application filed April 13, 1905. Serial No. 255,462.

To all whom it may concern:

Be it known that I, JAMES MACKAYE, of Cambridge, in the county of Middlesex and State of Massachusetts, have invented certain new and useful Improvements in Processes of Producing Chlorids of Carbon, of which the following is a specification.

This invention relates to a new and improved process for producing chlorids of carbon.

Figure 1 is a diagrammatic view of an apparatus constructed in accordance with my invention. Fig. 2 is a side elevation of the reaction chamber and its stacks. Fig. 3 is a top plan view of the reaction chamber and stacks shown in Fig. 2. Fig. 4 is a vertical sectional view of the reaction chamber and the connection of the chamber with its stacks. Fig. 5 is a cross-sectional view of the reaction chamber taken on the line 5—5 of Fig. 4 looking in the direction of the arrow. Fig. 6 is a cross-sectional view of the inlet portion of one of the stacks taken on either line 6—6 of Fig. 2. Fig. 7 is a cross-sectional view of one of the stacks taken on the line 7—7 of Fig. 2, showing the arrangement of the divided portion of the stack with its water-jacket. Fig. 8 is a view in perspective and partly in section, showing the arrangement of the divided portion of one of the stacks with its cooling chamber or water-jacket.

In practicing my process, I bring methane CH_4 into the presence of chlorin Cl_2 in a closed chamber filled with porous media, preferably granulated coke that has been treated to remove its sulfur and iron contents. By a proper control and regulation of the reaction I am able to produce chlorids of carbon, including chloroform, tetrachlorids of carbon, CCl_4 , also hydrochloric acid, HCl , and various by-products both continuously and commercially.

The reaction where tetrachlorids of carbon is produced may be expressed as follows:

where

CH_4 = methane, or the main ingredient of natural gas—

50 Cl_2 = chlorin, a gas—
 CCl_4 = tetrachlorids of carbon, a gas above 76 C.; solvent, non-explosive, and non-inflammable.

HCl = hydrochloric acid, a gas, soluble in water.

The methane and chlorin, if permitted to react without control, will not produce chlorids of carbon. This uncontrolled reaction may be expressed as follows:

where

CH_4 = methane, C = carbon,

Cl_2 = chlorin, HCl = hydrochloric acid.

While my process may be practiced in many forms of apparatus, I have found the arrangement shown diagrammatically in Fig. 1 and in detail in the other figures economical and efficient as to cost, capacity, and safety of operation.

Referring to Fig. 1, wherein there is illustrated diagrammatically my improved apparatus whereby my process may be carried out,—1 represents a gasometer for holding natural gas, a large percentage of which is made up of methane, as is well known. 2 represents a gasometer for holding chlorin, 3 represents a meter, 4 a regulator, 5 a drier, 6 a 3-way valve, 7 a pipe leading from the gasometer 1 to the meter 3, 8 a pipe leading from the meter 3 to the regulator 4, 9 a pipe leading from the regulator 4 to the drier 5, 10 a pipe leading from the drier 5 to the 3-way cock 6.

The meter 3, regulator 4, and drier 5 may be of any suitable preferred design or construction. The purpose of the drier and the meter are well known and require no description. The purpose of the regulator is to maintain a predetermined rate of flow of the contents of the gasometer 1 through the system.

12 represents a regulator, 13 a drier, 14 a pipe leading from the chlorin gasometer 2 to the regulator 12, 15 a pipe leading from the regulator 12 to the drier 13, 16 a pipe leading from the drier 13 to a 3-way cock 17. The regulator 12 is to maintain a predetermined rate of flow from the contents of the chlorin gasometer through the system. The drier 13 is like drier 5.

20 represents a suitable base or support for holding the reaction chamber 21.

22, 23 represent stacks each connected to one side of the reaction chamber 21, the said stacks and chamber constituting in effect one chamber. From the 3-way cock 6 a pipe 30 leads to the end of the stack 23 and a pipe 31 leads to the end of the stack 22, while from the 3-way cock 17 a pipe 32 leads to the end

of the stack 23 and the pipe 33 leads to the end of the stack 22. By this arrangement the methane and chlorin may be fed to the stack 23 through the pipes 30 and 32 or to the stack 22 through the pipes 31 and 33, the purpose of this arrangement being to enable the operator to feed the methane and chlorin as desired. The stacks 22 and 23 and chamber 21 consist essentially of a wall of any suitable material to resist the reactions involved and are filled with any suitable material, preferably coke, which is intended to prevent the reaction heretofore referred to, to wit:

and any reaction in the mixing zone. Each of the stacks 22, 23 connects at its lower end, as shown in the drawings, with the bottom of chamber 21. From the top of chamber 20 21 a pipe 50 leads and connects with a condenser 51.

52 represents a pipe connecting the condenser 51 with the condenser 53. A pipe 54 connects condenser 53 with condenser 55, 25 while a pipe 56 connects the condenser 55 with the pump 57, the pump acting as an exhaust to maintain the flow of gases through the system. The condensers 55 may be of any suitable design or construction to hold and condense the products of the reaction. The reaction chamber should be maintained in any preferred way at a temperature between 250° and 600° C.

The regulators 4 and 12, as shown, are connected together by shafts 12^a, 4^a and gears 4^b, 12^b, so that the said regulators travel together in predetermined order with relation to each other. Assuming the regulators 4 and 12 to have the same capacity under the 40 same speed and pressure, as the amount of chlorin in the mixture is greater than the amount of methane, the wheel 12^b is made smaller than the wheel 4^b. When using this arrangement above described, the ordinary 45 water gas meter may be used for the regulators 4 and 12.

From the foregoing it will be seen that the system starts with two branches, gasometer 1 for the methane, gasometer 2 for the 50 chlorin, the methane and chlorin branches uniting in the outer end of the stacks 22 and 23, the chlorin and methane being brought into the presence of each other at this point. From the end of the stacks 22 or 23 the apparatus proceeds as one system up to and including the exhaust pump 57, from which the uncondensed gases may be carried to any desired point. It will be seen that the exhaust pump 57 is effective throughout the 55 whole system, not only up to the chamber 21 but also through the methane and chlorin branch. At the exhaust end of the system the pressure is less than at the feed end, so to speak, which difference in pressure can be

varied as desired by varying the speed or work of the exhaust 57. An inspection of the diagrammatic view shows that I have one control for each branch, chlorin and methane, to wit, the regulators, a control for the regulation of the heat in the reaction 70 chamber, and a control for the rate of work, to wit, the exhaust.

My process is carried out as follows: The gasometers 1 and 2 being supplied respectively with natural gas and chlorin, the cocks 75 6 and 17 are operated to connect their respective ports with the end of the stack 22 or the end of the stack 23, the purpose being to conduct both the natural gas and the chlorin into the end of the same stack. The exhaust 57 is then started. This compels the flow of the natural gas and chlorin in predetermined quantities through their respective regulators 4 and 12, into the end of the stack 22 and stack 23 where the methane 85 and chlorin enter the material with which the stacks of the chamber are filled, forming a mixture and thereafter passing as a mixture to that point in the stack or the chamber where the temperature is sufficient to permit 90 the desired reaction to be accomplished. In practice the temperature for the reaction is about 400° C. but may vary from 250° to 600° C., depending upon the speed of the apparatus, the relative purity of the ingredients, etc.

Any desired means may be employed to establish in the reaction chamber the desired temperature. As the mixture approaches the zone of reaction in the chamber, or the 100 parts of the chamber having the required temperature, the reaction begins and is completed, the products of reaction passing out through the pipe 50. After the reaction has started, the zone of reaction works back 105 toward the end of the stack, due to the heat given off by the reaction. This phenomena enables me in some cases, to rely upon the reaction itself for the necessary heat after the reaction is once set up. In order to prevent the zone of reaction from extending too far into the stack and encroaching upon the mixing zone, I employ any preferred means for so controlling the temperature as to prevent the reaction zone from extending back 115 into the mixing zone, which rearward action if not controlled would manifestly interfere with the mixing and the efficiency of the apparatus and the method.

The tetrachlorid of carbon and hydrochloric acid together with the other products of reaction pass, as stated, through the pipe 50 into the condenser 51, where the gases are reduced to such a temperature below 76° C. that the tetrachlorid of carbon will liquefy, 120 so that it can be drawn off from the condenser. For commercial purposes the temperature of the gases should be reduced to the vicinity of 35° C. in order to liquefy the

hydrochloric acid sufficiently so that it can be drawn off in commercial form. The gases that remain uncondensed in the condenser 51 will in like manner be taken care of by 5 condensers 53 and 55, as many condensers being used as is necessary, the residual gases, if any, other than the tetrachlorid of carbon or hydrochloric acid being taken care of by the exhaust.

10 Referring to Figs. 2 to 8, wherein I have illustrated my improved form of reaction chamber 21 with its stacks 22, 23, 60 represents a pan, or other suitable receptacle, adapted to hold water and maintained on 15 any suitable frame or support, not shown. 61, 62 represent two slats arranged crosswise of the pan 60 and having a sufficient length to permit their ends to extend beyond the sides of the pan, as shown, in order to rest 20 upon and be supported by a suitable framework; not shown, independent of that which supports the pan. The lower portion of the reaction chamber is arranged between these slats, the latter each being arranged on 25 either side of the reaction chamber and underneath a ledge or sidewise extension of the reaction chamber, whereby the latter is supported by the slats independent of the pan. 63 represents a bar connected at its end by 30 bolts 64 with the underside of the slat 61 (see Figs. 3 and 4). 65 represents a complementary slat in like manner connected to the underside of slat 62 by bolts 66. 67, 68 represent two slats, one near each end of the pan 35 having their ends extending beyond the edge of the pan and adapted to rest upon the support which carries the slats 61, 62, or any other support independent of the support of the pan. 69 represents a slat connected at 40 its ends by bolts 70, to the underside of the slat 67 (see Fig. 2). 71 represents a slat connected at its ends by bolts 72 to the underside of the slats 68. The slats 61, 62 serve to support the reaction chamber and at the 45 same time the slats 63, 65, the latter together with the slats 69 and 71 serving to support inclined longitudinal slats 73. Three of the slats 73 are arranged at one end of the pan, three at the other, each set of three slats 50 forming in effect a grid, one set of the slats or grid supporting the inclined part 22^a of the stack 22, while the other set of slats on the righthand end of the pan support the inclined part 23^a of the stack 23.

55 By the described construction it will be seen that the water circulation can be maintained about the inclined parts 22^a, 23^a of the stacks and the lower part of the reaction chamber 21. The lower part of the stack 23 immediately above the inclined part 23^a is 60 divided, as shown in Figs. 2, 7, and 8, for a short distance to subdivide the cross-sectional area of the stack and increase the cooling surface by means of the chamber 76.

65 77 represents a water-jacket of any suit-

able material, arranged about the subdivided part of the stack 23. This chamber has a closed bottom through which the stack passes, but may be open at the top, and water circulation may be maintained in this chamber about the two branches 120, 121, of the stacks and through the chamber 76 between said branches by any desired means. The stack 22 may if desired be formed with a like subdivision provided with a like water-jacket, it being understood that the circulation in the pan 77 is or may be independent of the circulation in the pan 60. While I have shown in the drawings a stack divided into two branches, such subdivision may be 70 made into any desired number of branches, the idea being to subdivide the stack into a sufficient number of branches to enable the cooling media to maintain the desired temperature by dissipating the heat of the reaction. The upper end of the stack 23 is closed and provided with three inlet ports 80, 81, 82, the latter being for methane or natural gas and the ports 80, 81 for chlorin. Two diaphragms 83, 84, are arranged one on 75 either side of the port 82 and extend down a substantial distance into the stack, permitting the natural gas to enter the stack, but keeping it separate from the chlorin which enters through the ports 81, 80 on either side 80 respectively of the diaphragms 84, 83. The stack 22 in like manner is provided with ports 86, 87, for the chlorin and the port 88 for the natural gas. The stack 22 is further provided with diaphragms 89 and 90, corresponding to the diaphragms 83, 84. Each of the stacks and their branches 22^a, 23^a are filled with pulverized material 100 of any suitable kind to permit the mixing of the chlorin and natural gas without explosion. I have found in practice pulverized coke very 100 satisfactory for this purpose, care, however, being exercised not to have the coke pulverized so fine as to create powder to cause back pressure. The coke 100 in each stack extends substantially up to the point indicated by line 6—6, that is, above the lower ends of the diaphragms 83 to 84 and 90 to 89 so that the chlorin and natural gas are in contact with coke or other material before they come 105 in contact with each other.

The reaction chamber 21 is composed of a piece of soap-stone 90, through which is cut a rectangular hole (see Figs. 4 and 5) and is filled with powdered coke 100. While any 110 desired material may be used for the body of the chamber, I have found soap-stone very efficient to withstand the various phenomena attendant upon the reaction that takes place, as well as the action of the mixture and the 115 products of the reaction. The sides of the soap-stone block 90 are preferably covered with lead 92, which, at the bottom is bent under the lower end of the block, as shown in Fig. 4, then extended downward a short dis- 120 125 130

tance and then bent at an angle and extended to form the inclines 22^a, 23^a, and the stacks 22 and 23, thus making the chamber, the soap-stone and the stacks continuous.

5 97 (Fig. 4) represents a block of lead arranged in a pocket formed by the lead covering 92 and serves as a terminal. This block, as shown, is rectangular in shape and extends the whole length of the chamber, which at 10 this point is of lead.

102, 103 represent a row of carbon rods, one on either side of the chamber in the soap-stone. The lower ends of these rods are arranged in complementary recesses in the lead 15 terminal 97. The upper ends of the row of rods 103 are arranged in the carbon terminal 104 at the top of the chamber, while the upper ends of the rods 102 are arranged in the carbon terminal 105.

20 106 represents a carbon strip arranged between the two terminals 105, 104, and provided with a marginal lip, as shown, engaging the tops of the terminals in order to prevent its slipping downward.

25 110 represents a dome formed of lead arranged over the carbon strip 106, as shown, and over the chamber in the soap-stone. The ends of the sheet of lead forming this dome are carried down and inserted in a suitable recess in the soap-stone, as shown in Fig.

30 4. The upper edge of the sheet of lead 92 that covers the soap-stone is not turned down, in order to prevent any contact between this and the lead forming the dome.

35 112, 113 represent two bars one on either side and at the lower part of the dome. These bars are adapted to be clamped together by means of bolts 115 at each end, in order to bind the parts firmly in position, the 40 carbon strip 106 serving as an abutment against which the terminals 104 can be pressed.

116 represents a wire running from the top of the dome 110 to any suitable source of 45 power.

117 represents a wire running from one of the inclined members of the stacks, here shown as 23^a, to the source of power, the current passing from the source of power to the 50 stack, thence to the lead terminal 97, through the rods 102, 103 to the terminals 104, 105, to the dome 110, thence back. Any suitable instrumentalities, such as a switch, rheostats, etc., may be employed to regulate the current.

55 While I have made use of the term "tetrachlorid of carbon" as descriptive of the products of reaction, as carried on in my apparatus and by my process, I wish it understood that I have used such term by way of illustration, and not in any sense by way of limitation, since my process and apparatus are designed and intended for the production of all chlorids of carbon, including chloroform.

60 65 Having thus explained the nature of my

invention and described a way of constructing and using the same, though without attempting to set forth all of the forms in which it may be made, or all of the modes of its use, what I claim and desire to secure by Letters Patent is:—

1. The process of producing chlorids of carbon which consists in mixing gas and chlorin in the presence of a porous media, subjecting said mixture to a reacting temperature, maintaining the mixing zone separate from the reacting zone, and separating the products of reaction. 75

2. The process of producing chlorids of carbon which consists in mixing gas and chlorin in the presence of a porous media, preventing reaction in the mixing zone, subjecting said mixture to a reacting temperature, and separating the products of reaction. 80

3. The process of producing chlorids of carbon which consists in mixing gas and chlorin in the presence of a porous media, subjecting said mixture to a predetermined temperature by electrical means, maintaining the mixing zone separate from the reacting zone and separating the products of reaction. 85

4. The process of producing chlorids of carbon which consists in mixing gas and chlorin in the presence of granulated coke, subjecting said mixture to a reacting temperature, maintaining the mixing zone separate from the reacting zone, controlling the temperatures of both zones, and exhausting 100 at the delivery end of said reacting zone to maintain a uniform action and separating the products of reaction. 95

5. The process of producing chlorids of carbon which consists in mixing gas and chlorin in the presence of a porous media, subjecting said mixture to a reacting temperature, controlling the temperatures of the mixing and the reacting zones, maintaining the reacting and mixing zones separate, and 105 separating the products of reaction. 110

6. The process of producing chlorids of carbon which consists in bringing natural gas and chlorin together in a closed chamber containing granulated coke, controlling the 115 temperature of said chamber, subjecting said mixture to a reacting temperature, maintaining the reaction zone separate from the mixing zone, regulating the temperatures of the mixing zone and reacting zone, and 120 separating the products of reaction.

7. The process of producing chlorids of carbon which consists of bringing natural gas and chlorin together continuously in a closed chamber containing granulated coke, 125 exhausting said mixture from said chamber to a reacting chamber, subjecting said mixture in the reacting chamber to a reacting temperature, controlling the location or zone of reaction with reference to the zone of 130

mixing, controlling the temperatures of both zones, exhausting at the delivery end of said reaction zone to maintain a uniform and continuous action, and separating the products of reaction.

8. The process of producing chlorids of carbon which consists in mixing natural gas and chlorin in a closed chamber in the presence of a granulated porous media, controlling the temperature of said chamber, exhausting said mixture to a reaction zone in

said chamber, subjecting said mixture to a reacting temperature, controlling the temperatures in the mixing and reacting zones, and separating the products of reaction.

In testimony whereof I have affixed my signature, in presence of two witnesses.
